Primary Examiner — Eric Goodman*Assistant Examiner* — Sanjeev Paul(74) *Attorney, Agent, or Firm* — Briggs and Morgan,
P.A.; Gerald E. Helget(57) **CLAIM**

The ornamental design for an adjustable backrest for a tub, as shown and described.

DESCRIPTION

FIG. 1 is a front perspective view showing my new design for an adjustable backrest for a tub;

FIG. 2 is a rear elevational view;

FIG. 3 is a left side elevational view which is a mirror image of the right side elevational view;

FIG. 4 is a front elevational view;

FIG. 5 is a top plan view; and,

FIG. 6 is a bottom plan view.

The broken line drawings of the tub, amputee person and rib gussets are for environmental purposes only and form no part of the claimed design.

1 Claim, 2 Drawing Sheets(56)
